UNITED STATES PATENT OFFICE.

JOHN F. MCCOY, OF BROOKLYN, NEW YORK; MARY MCCOY ADMINISTRATRIX OF SAID JOHN F. MCCOY, DECEASED.

AUTOMATIC SAFETY SIGNALING AND BRAKING DEVICE FOR TRAINS.

1,215,952.

Specification of Letters Patent. Patented Feb. 13, 1917.

Application filed October 1, 1914. Serial No. 864,403.

To all whom it may concern:

Be it known that I, JOHN F. MCCOY, a citizen of the United States, and a resident of the city of New York, borough of Brooklyn, in the county of Kings and State of New York, have invented a new and Improved Automatic Safety Signaling and Braking Device for Trains, of which the following is a full, clear, and exact description.

My invention has special reference to an improved automatic safety signaling and braking device for trains.

The invention comprehends the provision of an improved, positively operating and efficient mechanism carried by the locomotive or train and coöperative with the brake system thereof whereby an automatically operable tripping device moved simultaneously or in conjunction with the usual semaphore or other track signals constituting the "home" signaling apparatus is adapted to coöperate with a valve throwing or actuating mechanism carried by the locomotive or train to open an auxiliary train pipe for relieving portions of the mechanism of train line pressure so as to cause the actuating of the throttle lever for cutting off the steam supply and applying the brakes in the event the engineer or trainman should attempt to pass a danger signal; the throttle lever actuating mechanism constituting a pneumatic device operable without wasting the train line pressure and capable of control so as to regulate the setting or application of the brakes, whereby unnecessary jar is eliminated, while provision is made for the disengagement of the locking mechanism of the lever successively preceding the throwing of the throttle lever for cutting off the supply of steam to the cylinders, while at the same time preventing injury to the engineer when the lever is so shifted without warning.

The invention further comprehends the provision of a braking mechanism of the character specified which when operated by a trip connected with each semaphore or signaling device will necessitate the engineer getting out of his cab and setting the trip device so as to close the auxiliary train line pipe in order to release the brakes and permit continued travel of the train, thereby preventing the engineer from rendering the device inoperative when once actuated, from the throttle lever or brake valve or mecha-

nism associated with the air brake system, and rendering the mechanism tamper-proof, positive in operation and efficient in use.

With the above and other objects in view, the invention resides in the peculiar combination and arrangement of parts to be hereinafter more fully described, illustrated and claimed, it being also an object to provide a device which is simple in construction, durable and efficient in operation and not likely to get out of working order.

Reference is to be had to the accompanying drawings forming a part of this specification, in which similar characters of reference indicate corresponding parts in all the views, and in which—

Figure 1 is a side elevation of a locomotive in phantom and partly broken away, with my improved automatic safety signaling and braking device applied thereto as associated with the usual air brake system;

Fig. 2 is a top view illustrating the application of the appliance;

Fig. 3 is an enlarged side elevation partly broken away of a valve throwing or operating device suspended from a locomotive and adapted for engagement with a trip;

Fig. 4 is a front elevation of the structure shown in Fig. 3;

Fig. 5 is a plan view thereof with the sill of the locomotive omitted;

Fig. 6 is a sectional view taken on the line 11—11 of Fig. 3;

Fig. 7 is an enlarged vertical sectional view of the relief valve employed on the auxiliary train line pipe;

Fig. 8 is an enlarged vertical sectional view of the pneumatically actuated mechanism for throwing the throttle lever, the same being in a retracted position and illustrated in connection with the lever;

Fig. 9 is a sectional view taken on the line 14—14 of Fig. 8;

Fig. 10 is a sectional view taken on the line 15—15 of Fig. 8 and showing the throttle lever in plan before being shifted or thrown;

Fig. 11 is a sectional view taken on the line 16—16 of Fig. 10.

In illustrating the application of the improved automatic safety signaling and braking device, a locomotive 1 is shown, the same being equipped with the usual or any standard air brake system including the usual pump 2, exhaust pipe 3, main reser-

voirs 4 having communication with the pump and with the train pipe 5 containing air under train line pressure and extending forward to the usual flexible coupling 6 at the pilot of the locomotive. The pump is in communication with the engineer's brake valve 7 which leads to the train line pipe 8 having a flexible coupling 9 including the usual form of angle cock for coupling the same to the train line pipe leading from the tender of the locomotive. The system further includes an equalizing reservoir 10 which, together with the train line pipe 8 beneath the cab and leading from the brake valve 7, has communication with the usual triple valve 11, driver-brake reservoir 12 and truck brake reservoir 13 associated with the main reservoirs and controlled in the usual manner. The brake shoes operating on the drive wheels are actuated from the driver-brake cylinders 14 which are coupled to the train pipe leading from the brake valve, while the usual signal pipe is indicated by the numeral 15 and extends forward to the pilot to be coupled in the usual manner and controlled by a stop cock 16.

The improvement constituting the invention comprises a pneumatically actuated device 17 having operative connections with the throttle lever 18 for throwing the latter and cutting off the supply of steam to the operating cylinders of the locomotive. For this purpose an auxiliary train pipe or exhaust 19 is run along the side of the boiler 30 and then downwardly beneath and inwardly of the engine cylinders and beneath the sill 20 where it is provided with an exhaust valve 21 supported by or suspended from the sill to be operated by a valve throwing device 22 to be hereinafter more fully and specifically described. The exhaust pipe 19 is tapped into a lead or supply pipe 23 which has operative connection with the pneumatically operated device 17. Between said device and the train pipe 8 leading to the tender and cars of the train, a cut-off 24 is mounted in the lead or supply pipe 23, whereby the said lead or supply pipe as well as the auxiliary train pipe or exhaust 19 may be supplied with air under train line pressure or entirely cut off therefrom so that during the operation of the device, as will be later described, wasting of the train line pressure will be prevented when the device is actuated for throwing the throttle lever, the conservation of such pressure obviating the necessity of renewing the whole pressure before permitting the train to proceed.

Opposing the air supply under pressure through the lead or supply pipe 23, the mechanism of the pneumatically operated device 17 for throwing the throttle lever is constantly supplied with air under train line pressure through a lead or supply pipe

25, the same being cut into or connected with the auxiliary train line pipe or exhaust 19 between the train line pipe 8 and the cut-off 24 and controlled independently of the train line pipe 5 extending forwardly to 70 the pilot. The train line pipe 5 is in direct communication with the pipe 8 which extends to the tender and is directly controlled from the engineer's brake valve 7 in the usual manner, for admitting air under 75 pressure to apply the brakes or to release the same.

The throttle valve is indicated by the numeral 26 and is connected to the throttle lever 18 by a rod 27, the throttle lever moving horizontally in the cab in rear of the boiler through which the rod 27 is passed by means of a piston packing 28. The throttle lever is vertically pivoted for horizontal movement upon a toggle bracket 29, 85 the fulcrum of the lever being indicated by the numeral 30, while the lever is in turn pivoted to a notched segment 31 having oppositely extending sockets 32 and 33 receiving and having removable or pin connection with the rod 27 and a plunger 34, respectively. The pivotal connection between the throttle lever 18 and the segment 31 is indicated by the numeral 35, it being thus observed that when the throttle lever 95 is shifted to operate the throttle valve for admitting steam to or cutting off the same from the cylinders, the lever will move on its fulcrum 30 and thereby shift the segment together with the rod and plunger 100 while the lever moves with respect to the notched edge of the segment.

The lever carries a latch mechanism consisting of a handle 36 pivoted to the lever and connected by a rod 37 to a locking 105 block or dog 38, notched to coöperate with the notched segment 31 and slidably mounted on the lever as shown at 39. This connection is made through the medium of an interposed coupling 40 which has an 110 apertured sleeve-formed end 41 receiving the rod 37 therethrough, while the rod is in turn threaded for the engagement of a nut 42 adapted to permit upward movement of the locking block or dog and the coupling 115 on and with respect to the rod 37 without moving the handle 36, as well as to adjust the degree of movement of the locking block or dog. The rod 37 operates through an apertured bracket 43, and engaged on the rod between the bracket and the end portion 41 of the coupling is an expansible coiled spring 44 normally tending to hold the notched locking block in engaging position and necessitating that the block together with the coupling, be shifted against the action thereof in order to permit the lever to be thrown. The segment is provided with laterally projecting angular guides 45 indicated as one form of means 125 130

for slidably connecting a shifting and locking plate 46 thereto near each end, the plate being shown as a substantially I-shaped member and being retained at a spaced distance from the notched segment by grooves 47 in the guides. The throw lever 18 thus operates between the segment 31 and the plate 46 and has formed with its locking block or dog 38, a locking projection 48 which is also slidably engaged with the lever as by means of pins 49 carried by the lever and passing into slots 50 in the block and projection which may, as illustrated, be formed into a single casting. The plate 46 is provided with a recess or notch 51 in its curved free edge so that when the throttle lever is thrown to close the throttle valve, or in a reverse position to that shown in Fig. 10 of the drawings, the projection 48 will drop into the recess simultaneously with the engagement of the locking block or dog with the notches of the segment, due to the shifting of the plate with respect to the segment, in a manner to be hereinafter more fully described.

The pneumatically operated device 17 for operating or throwing the throttle lever after having disengaged the latch mechanism, comprises a suitable casting forming a cylinder 52 with valve casings 53 and 54 integral therewith or mounted thereon, the casting being supported upon a bracket 55 in rear of the throttle lever or otherwise properly arranged and supported in accordance with the particular type of locomotive to which the mechanism is affixed, it being understood that the device is one of general application to all classes of locomotives as now constructed. Single plates 56 and 57 are provided to form the cylinder heads of the cylinder 52 and the end of the valve casings 53 and 54, the parts being suitably connected as shown at 58. Slidably mounted in the cylinder 52 is a piston 59 having a hollow piston rod 60 threaded or otherwise detachably connected thereto as shown at 61, and said hollow piston rod operates through a bearing 62 and is connected by means of an angular arm 63 with a bell crank lever 64 pivotally carried from the connection 35 and having an inclined arcuate slot 65 engaging a pin 66 projecting from the face of the plate 46 in such a manner that when the piston 59 is moved forward it will move the plate to disengage the locking dog and projection and permit movement of the lever without interference. During this movement the coupling member 40 will operate through a strap member 67 carried by the lever and the spring will be compressed against the bracket 43 while the rod 37 remains stationary and therefore does not move the latch handle on its pivot so that injury to the engineer, should he have his hand on the throttle lever, is prevented.

Also working or slidably mounted in the cylinder 52 is an outer piston 68, both of said pistons having proper packing rings to afford an air tight connection with the interior face of the cylinder and the piston 68 having a flange 69 and concussion plugs 69' serving to space the pistons apart in the same or at their rearward limit or retracted as shown in Fig. 8, the pistons being regulated by regulation or control of the air pressure. The piston 68 is mounted on a reduced tapered portion 70, the plunger 34 coupled to the socket 33 as heretofore described and the plunger is provided with a reduced portion 71 operating through the attaching end of the hollow piston rod 60. The plunger 34 is threaded as shown at 72 for the engagement of a nut 73 thereon to secure the piston 68 on the tapered portion of the plunger against the shoulder 74 and the plunger is extended beyond the plate 56 by operation through a bearing 75 therein. The extended end of the plunger is hollowed out as shown at 76, the passage or bore thus provided communicating with the space between the pistons by lateral branches 77 for a purpose to be hereinafter more particularly specified.

The plate 56 is provided with an exteriorly threaded flange 78 projecting therefrom concentric to the center of the cylinder 52 around the extended end of the plunger 34 so as to receive the enlarged end portion 79 of a by-pass casing 80 in the form of a tube having a closed outer end with a by-pass 81 leading from the space between said casing and the hollow extension of the plunger 34 through the enlargement and laterally to communicate with a passage 82 meeting therewith and extending through the plate 56 or head of the cylinder 52 and then horizontally to communicate with the interior of the valve casing 54 through a port 83. The by-pass casing 80 is suitably attached to the plate or cylinder head 56, as by means of a flanged nut 84 engaged on the exteriorly threaded flange 78 and overlying the enlargement 79 to retain the latter in air-tight connection with said plate, whereby a continuous passage is established through the port 83, passage 82, by-pass 81, the space between the casing 80 and the hollow portion of the plunger 34, then through the bore 76 of the plunger and finally through the branch outlets 77 to the space between the pistons 59 and 68. The throw of the lever 18 is very slight at the point of pivotal connection of the lever with the segment and thus with the sockets connecting the same to the hollow piston rod 60 and the plunger 34, and in order to return the pistons to the rearward positions or to retract the same, an expansible coiled spring 85 is mounted on extensions of the piston head or plate 57 and the piston 59, said spring also

surrounding the hollow piston rod 60 and the plunger 34 disposed therethrough, thus providing means to hold the lever in a position with the throttle valve open. The 5 spring 85 is made relatively weak so as to permit manual operation of the throttle lever, openings 85' being provided to prevent the compression of air in back of the pistons or the formation of a vacuum.

10 The lead or supply pipe 23 is provided with branches 86 and 87 communicating with the interior of the valve casings 53 and 54, respectively, while the lead or supply pipe 25 is provided with branches 88 and 15 89 correspondingly communicating with the interior of the valve casings 53 and 54 respectively. These casings are mounted upon the cylinder 52, as is more clearly shown in Fig. 8 of the drawings, so that the intermediate wall 90 is provided for accommodating the ports and passages including the passage 82 which extends into the end plate of cylinder head 56, and the port 83 heretofore described. Communication is established 20 between the main reservoir and the interior of the valve casing 54 by a pipe 91 which is illustrated in Fig. 1 of the drawings as connected to the lead of the engineer's brake valve, the connection of the 25 pipe 91 with the casing 54 being to one side of its longitudinal center, while an air exhaust port 92 is provided in said casing nearer its other end. The passage 82 communicates through the port 83, consisting 30 of a transverse recess in the interior wall of the casing 54 and at the bottom thereof, with the interior of said valve casing about midway of its length. This port 83 is widened toward one end, as shown at 35 93, and intermediately is provided with a partition 94 dividing the port so that communication is established through one end thereof opposite to the widened portion which has communication with the passage 82, with 40 the space between the cylinder head or plate 56 and the piston 68, by means of a passage 95 extending through the wall 90 to one side of the passage 82 and directed angularly for communication with said space in 45 50 distinction to the communication of the passage 82 between the pistons, as heretofore described.

Leading from the valve casing 53 is a port or duct 96 which has communication with a 55 passage 97 establishing communication with the train pipe through a pipe 97', so as to maintain the same constantly under train line pressure. Slidable in the casings 53 and 54 are tandem valves 98 and 98'. These 60 valves are of similar construction and comprise a pair of valve disks 99 and 99', 100 and 100', and further valve disks 101 and 101', which are connected in spaced relation by bolts 102 and 102' with intermediate 65 spacing members 103 and 103' shaped like

spools, so that the disks 100 and 100' are disposed intermediately and equi-distantly from the disks 99 and 101 and the disks 99' and 101' respectively. The plate 56 is provided with a pair of extensions 104 producing shoulders for contact by the casings 53 and 54 normally spaced from the disks 99 and 99', the disks 99—99'—100—100' being of the same diameter while the disks 101 and 101' are of larger diameter and operate 70 in enlarged portions 105 of the valve casings limited by shoulders 106 produced by said enlarged portions with the smaller portions, while all of said disks are provided with suitable packing rings 107 forming airtight 75 connection with the interior walls of the casings. A safety blow-out valve 108 is carried by the valve casing 53 at a point adjacent to the disk 100 and between the disks 99 and 100, while communication is established 80 between the space beyond the disk 101 or between said disk and the adjacent end of the casing 53, through a bleed duct 109 and through the port 96 with the space between the disks 100 and 101 and also with 85 the pipe 97' through the passage 97 as indicated by the dot and dash lines in Fig. 10 of the drawings to maintain the parts under train line pressure.

The pipe 97' is tapped into the train line 90 pipe 5, communicating with the pipe 8 leading therefrom and is preferably of larger size than the leads or supply pipes 23 and 25, so as to constantly supply air under pressure from the train pipe to the space between the disks 100 and 101 and thereby act to balance said disks and due to their exposed portions facing each other, being of the same size, no tendency will be exerted to force the valves at either end of the valve 105 casing. However, as air is supplied through the pipes or leads 23 and 25 under equal pressures, the air entering the valve casings from the pipe 23 through the branches 86 and 87, will due to the disks 101 and 101' 110 being larger than the disks 99 and 99', overcome the action of the air pressure acting against the latter disks by entering the casings through the branches 88 and 89, thus holding the valves to the extreme left in 115 Figs. 8 and 10 of the drawings.

In order to dispose the valves in these positions, the cut-off 24 is open to admit air to the lead or supply pipe 23 under the same pressure that exhausts into pipe 25 and 120 when the disks 101 and 101' have engaged the shoulders 106 the cut-off is closed, but such air under pressure will have been admitted to the auxiliary train pipe or exhaust 125 19 and while the valve 21 is closed, the same pressure will be maintained in the pipe 23 to retain the valves 98 and 98' in the positions set forth. The cut-off 24 is then closed so as to cut off communication of the pipes 19 and 23 with the train line pipe supplied 130

with air from the main reservoir, so that while the valves 98 and 98' are in the positions named, the air under pressure in the pipe 91 will be discharged between the disks 5 99' and 100' and since equal pressure will be exerted against both, this will have no tendency to shift the valve 98' as a whole and the escape of such air under pressure beyond the disks 99' and 100' is prevented. The air under pressure from the train line pipe 5 discharged through the pipe 97' and passage 97, will also be discharged through the port 96 and between the disks 100 and 101, so as to similarly serve to exert similar pressures 10 against these disks and therefore not act to shift the valve 98 as a whole. A slight quantity of this air, however, will escape through the port 96 and through the bleed duct 109 to the interior of the valve casing 53 and 15 into the enlarged portion thereof beyond the disk 101 and thereby serve to compensate for any leakage in the pipes 25 and 23, so that the valves 98 and 98' will be maintained in the position stated when the brakes are unapplied and the throttle lever is in the position shown in Fig. 10, with the throttle valve open to admit steam to the cylinders. However, as previously stated, by manually disengaging the locking dog or pawl 38 from 20 the segmental rack 31, the throttle lever may be shifted against the action of the spring 85 to close the throttle valve and cut off the supply of steam to the cylinders without interfering with the positions of the valves, as 25 for instance when the engine is not driving or is drifting and precaution is taken in the usual way to open the cylinders to permit a free exhaust, as for instance by the use of any well known type of drifting valve.

40 While the valves 98 and 98' are held in the positions specified, the safety blow-out valve or exhaust 108 will be positioned adjacent to the disk 100 and between it and the disk 99, so as to be entirely cut off from 45 the air pressure supplied to the casing 53 and in this manner, a reduction of air in the train line pipes 5 and 8 will be prevented, due to any escape through the pipe 97', since the quantity of air which will escape through the bleed duct 109 would be 50 very slight and will not serve to reduce the air pressure to any appreciable degree or to any amount that will not be readily overcome by the action of the air pumps, which 55 normally maintain the air under predetermined pressures. Heretofore it was common to maintain the train line pressure at 70 pounds per square inch, whereas at present on high-powered locomotives, a pressure of 90 pounds per square inch is 60 usually maintained and the same pressure is similarly advanced from 175 pounds per square inch to 190 pounds per square inch and up to 205 pounds per square inch, but 65 the present invention is equally applicable

to either type of locomotive with slight modifications in the parts as may be found necessary.

In order to apply the brakes and cut off the throttle valve, it is necessary to reduce 70 the pressure acting on the disks 101 and 101' and since the cut-off 24 closes the communication from the train line with the pipes 19 and 23, it is necessary to reduce said air pressure from the exhaust pipe 19 by opening the valve 21 and maintaining said valve in an open position. In operation, the effect of reducing the pressure in the pipe 19 by exhausting the air therefrom, would result in a corresponding reduction of the 75 pressure in the pipe 23 and from behind the disks 101 and 101', so that the excessive air pressure acting against the disks 99 and 99' will serve to shift the valves 98 and 98' in the opposite directions and cause the disk 80 101 to move beyond the end of the bleed duct 109, which communicates with the enlarged portion or bore of the casing 53, so that any air discharged therethrough will pass between the disks 100 and 101 and exert 85 a slight tendency to hold the valve 98 shifted to the right hand extreme. The air entering through the pipe 97' from the train line pipes 5 and 8 controlling the application of the brakes of the cars of the train will be 90 discharged through the port 96 and will escape through the exhaust or blow-out valve 108, due to the movement of the disk 100 beyond the port 96 when the valve 98 is shifted in the manner described, the port 100 95 100 and the exhaust 108 both communicating with the space between the disks 99 and 100, as will be readily apparent. The effect of this is to apply the brakes, but in order to simultaneously operate the throttle lever to 105 cut off the throttle valve, the excessive air pressure acting against the disk 99', will similarly shift the valve 98' to the extreme right, so that whereas the pipe 91 establishing communication between the main reservoir and the interior of the valve casing 54 in front of the disk 100' communicated with the casing between the disks 99' and 100' and in such a manner that the disk 100' separated this pipe from the port 83 to cut 110 off communication of the latter with the air supply under pressure and permitted the free exhaust of the air between the disks 100' and 101' through the exhaust port 92, the disk 100' will have been shifted beyond 115 or to uncover the port 83 and establish communication between it and the supply pipe 91. In shifting in this manner the valve 98' as a whole, the intermediate disk 100' will first uncover the widened portion 93 of the port 83 to one side of the partition 94 and thereby admit air through the passage 82, by-pass 81, into the casing 80 and then through the hollowed out end 76 of the plunger 34 and finally through the lateral 120 125 130 135 140

branches 77 to the space between the pistons 59 and 68. Due to the fact that these pistons are held normally spaced apart, the air under pressure will act to shift the piston 59 against the hollow piston rod 60 by reason of its communication with the bell crank lever 64 to swing the latter on the pivot 35 and shift the plate 46 by reason of the pin and slot connection of the lever or shifting 5 cam 64 with the plate 46, so that the locking dog or block 38 will be disengaged from the segmental rack by the movement of the projection 48 under the action of the shifting plate. After the latching or locking device 10 of the lever is thus released, the disk 100' will have moved beyond the port 83 to admit the air under pressure through the narrow portion thereof at the opposite side of the partition to discharge air under pressure 15 through the passage 95 and into the cylinder 52 in front of the piston 68 and thereby cause it to be shifted behind the piston 59, a small interval of time after the piston 59 has been shifted. The shoulder produced 20 by the reduced portion 71 of the plunger 34 engaging the corresponding shoulder produced by reducing the bore of the hollow piston rod 60, where the portion 71 operates therethrough at its attaching part with the piston 59, serves to limit the initial movement 25 of the piston 59, independent of the piston 68 and after the piston 68 is shifted it will contact with the piston 59 and the two will move simultaneously against the 30 action of the spring 85, so that the locking device of the lever having been disengaged, the lever will swing on its pivot to the opposite limit from that shown in Fig. 10 of the drawings, so as to close the throttle 35 valve. The lever, however, may be operated so as to dispose it in this position or any intermediate position normally against the action of the spring 85 without disturbing the positions of the valves 98 and 98' and 40 furthermore should the lever be shifted as described while the engineer is grasping the throttle lever and latch handle 36, the lever may be shifted without moving the handle, so that injury to the operator's hands will 45 not occur.

The range of movement of the plate 46 on the segmental rack 31, when the former is shifted by movement of the piston 59, rod 60 and bell crank lever or slotted cam 64, 55 is sufficient to disengage or unseat the locking dog or block 38 from the teeth of the rack and the throw of the handle 36 is also sufficient to unseat said dog to permit manual operation of the throttle valve by the 60 lever 18, but when the dog is unseated pneumatically and the lever thrown, the dog will engage the rack teeth and the projection 48 will drop into the notch 51. Since the plate 65 46 has been shifted, the throw of the handle 36 will be insufficient to unseat the projec-

tion from the notch, so that the lever cannot be thrown to operate the throttle valve for starting the engine. Furthermore, the lever cannot be operated against the air pressure acting on the pistons 59 and 68 and thus the 70 device must be reset by closing the valve 21 and opening the valve 24 to admit air under pressure equally at the ends of the valves 98 and 98', thus moving these valves and the pistons 59 and 68 to their initial or normal 75 positions, assisted by the spring 85. The absolute necessity of the engineer or trainman getting out of his cab or train and on to the ground to start the locomotive or train is thus made imperative and the device 80 thereby rendered fool-proof, reliable and positive in operation.

When the valve 21 is closed, this being necessitated in order to permit continued travel of the train, the cut-off 24 is opened in 85 order to permit air under pressure to move the valves 98 and 98' to their initial positions. This is due to the fact that the blow-off valve 108 is designed to prevent the escape of air at and below the pressure of 45 pounds per 90 square inch, so that the pressure within the train pipes is conserved and when the valves 98 and 98' are returned to their initial positions by opening the cut-off 24 after the valve 21 has been closed, the air behind the pistons 59 and 68 will escape to the atmosphere through the exhaust port 92 which communicates with the space behind the disks 100' and 101' when the valve 98' as a whole is shifted to the left to cut off communication 100 between the pipe or lead 91 with the port 83. The widened portion 93 of the port 83 is increased in width for a considerable portion of its length, so that the air will rush through the port and passage 82 and positively insure shifting of the piston 59 to release the locking mechanism of the throttle lever prior to the throwing of the lever.

As heretofore described, the valve 21 is supported beneath the sill 20, the location 110 and manner of supporting the valve depending upon the particular type of locomotive or car to which the device is applied. As shown, the valve embodies a casing 110 having an attaching flange 111, which is bolted 115 to the sill as shown at 112 and the valve has an internally threaded attaching portion 113 for communication with the auxiliary train pipe or exhaust 19, which as heretofore stated, extends to the forward part of the 120 locomotive or particular type of rolling stock, as is clearly shown in Figs. 1 and 2 of the drawings. The other side of the casing is provided with an outlet 114 through which the air escapes when the valve is open. 125 The valve casing is provided with an angular partition wall 115 normally separating the inlet and outlet portions thereof, but provided with an opening 116 around the bottom portion of which at the edge of the 130

opening, a seat 117 is formed for engagement by a valve 118. This valve is provided with a hollow stem 119 having an integral piston 120 movably mounted within the casing in a hollow space having a dome-like top as shown more particularly in Fig. 7 of the drawings. Removably secured in the bottom of the casing as by threading the same into an extension thereof, as shown at 10 121, is a plug 122 having a guide 123 for the stem 124 or a valve 125.

The stem above the valve proper operates through the hollow stem 119 of the valve 118 and said stem 124 is provided with a 15 plurality of spiders 126 forming a bearing against the bore of the hollow stem, while the valve 125 is held seated against the lower end of the valve 118 in a seat formed by the bore of the stem which communicates with 20 the top and bottom faces of the piston 120 and the valve 118 respectively, so as to prevent the escape of air around the stem and above the piston to unseat the valve 118 and thus normally to prevent the exhaust or 25 escape of air from the pipe 19 for the purpose heretofore described. Journaled horizontally beneath the sill 20 is a cam shaft 127 which has bearings in hangers 128 near the ends of the sill and suitably bolted to the 30 latter, as shown at 129, to be suspended from the bottom of the sill, as is more clearly shown in Figs. 3 and 4 of the drawings. The shaft extends through the valve casing 110 and carries a double-point cam 130 normally engaging the upper end of the stem 124, so that the rotation of the shaft in either direction for a slight degree, will operate to depress the valve 125 and permit the 35 discharge of air into the casing above the piston 120, so that the air pressure acting thereon will unseat the valve 118 downwardly and hold this valve in an open position to permit continued exhaust or escape of the air under pressure through the outlet 40 45 114 to reduce the air pressure in the pipes 19 and 23 to accomplish the operation hereinbefore described.

Mounted at each end of the shaft 127 is an engaging device for coöperation with a 50 tripping means for turning the shaft and applying the brakes as described, which engaging member comprises a valve-throwing device 22 as heretofore described, in the form of an angular frame with oppositely 55 inclined front and rear portions extending in the direction of travel of the train or parallel with relation to the tracks. Each end of the engaging member is bifurcated, as shown at 131, the bifurcations flaring 60 toward the free ends and bottom edges of the furcations and divided by a central portion 133 having inclined bottom walls 134, tapering toward the center and bottom edge of the engaging member. The opposed faces 65 of the furcations communicating with the

bifurcations are provided with serrations or teeth 135, in the present instance shown traversing the ends at either side of the center of the engaging member at right angles to the lengths thereof, but the essential feature is that said faces are provided with receiving surfaces for a purpose to be hereinafter more fully made apparent. At the center of each engaging member is an apertured ear 136, pivoted to each hanger 128 75 as shown at 137, so as to rock thereon and each end of the shaft 127 carries a cross arm 138 fixed thereto and provided with oppositely curved ends for pivotal connection with the engaging member at either side 80 of the pivot 137 through apertured lugs 139, as by means of links 140. In this manner, the rocking of the engaging member of the valve-throwing device, will result in the turning of the shaft 127 through 85 the instrumentality of the cross arm 138, thus to rotate the cam 130 depending upon the direction of travel of the train and the cam will serve to unseat the valve 125 by depressing the stem thereof for the 90 purpose of opening the valve 118 and exhausting the pipes 19 and 23 of air to close the throttle valve and apply the brakes, as heretofore described. The purpose of disposing the opposite portions of the engaging member of the valve-throwing device or slanting the same, is to permit the same to pass snow without operating the valve, and especially where the snow gets under the tread boards at a crossing and acts to 100 pry up the same or to cause the boards to swell. The shaft 127 is held against shifting longitudinally by jam nuts 141, secured thereto on opposite sides of the valve casing as shown in Fig. 4 of the drawings. 105

Although the engaging member of the valve-throwing device is constructed so that accidental throwing thereof is obviated and to overcome the serious objections to devices heretofore provided for applying the 110 brakes of a train by exhausting the train line, means are provided for special co-action with said valve-throwing device to apply the brakes and close the throttle valve to cut off the supply of steam to the cylinders adjacent to the usual home signals and which are coöoperative with the latter, so as to be set in position to trip the valve-operating device by contact with the engaging member thereof, so that if the signal is set 115 at danger, the engineer may not pass the signal by inadvertence, accident or mistake or purposely do so. As shown in Fig. 2 of the drawings, the shaft 127 as described extends to opposite ends of the sill and at 120 each end is provided with an engaging member, forming a part of the valve-throwing device, so that the valve may be turned from either side of the roadbed and the device adapted to an equipment suitable for a 125 130

single track line where the trains travel in either direction. Means are also provided for contact with the engaging member at various intervals between the home and distance signals for operating the valve-throwing device to meet with various requirements and exigencies brought about by traffic conditions or conditions of the tracks, as well as to provide for the setting of signals to warn an approaching trainman or engineer as to the conditions existing in advance of his train, or in any of the various blocks, into which every well regulated road is divided.

Having thus described my invention, what I claim as new and desire to secure by Letters Patent is:—

1. The combination of a train including a locomotive having a throttle valve, a lever for operating the same, an air brake system for the train including air supply means carried by the locomotive, a pneumatically operated device associated with the air brake system and the throttle lever, an auxiliary train line pipe associated with the air brake system and extending to the pilot of the locomotive, an exhaust valve associated with said pipe, and a valve throwing device for the valve adapted to coöperate with a tripping device along a track, said valve throwing device embodying a shaft associated with the valve, engaging members having inclined bifurcated portions, said engaging members being pivotally mounted and operatively connected to the shaft for rotating the same in opposite directions to operate the valve upon engagement of the tripping device with an engaging member when the train is traveling in either direction.
2. An automatic power cut-off and braking device for trains including a controlling valve having a lever, a latch for the lever, a train line pipe supplied with air under pressure, a pneumatically operated device including a piston connected to the lever, a valve associated with the train line pipe and for actuating the same and also including a piston for releasing the latch piston, an auxiliary train line pipe leading from said train line pipe, means for establishing communication between said train line pipe and the auxiliary train line pipe for cutting off the same, a trip valve associated with the auxiliary train line pipe for exhausting the air therefrom, a valve communicating with the auxiliary train line pipe, said first mentioned valve also communicating therewith and adapted upon the reduction of pressure in the auxiliary train line pipe to cause the operation of the piston to move the controlling lever to an inoperative position and permit the escape of air from the train line pipe for applying the brakes.
3. An automatic power cut-off and brak-

ing device for trains, comprising the combination with a locomotive having engine cylinders, a throttle valve controlling the supply of steam to the cylinders and a lever for operating said throttle valve, said lever having a latch mechanism; of a train line pipe supplied with air under pressure, a valved exhaust pipe leading therefrom and having an exhaust valve disposed in position to be tripped in passing an obstruction, a cylinder, a pair of pistons working in the cylinder and operatively connected to the lever and latch mechanism respectively, and valves communicating with the cylinder, train line and exhaust pipe for initially releasing the latching mechanism and operating the lever to cut off the throttle valve and permitting the escape of air from the train pipe upon the opening of said exhaust valve to simultaneously apply the brakes.

4. An automatic power cut-off and braking device for trains, comprising the combination with a locomotive having engine cylinders, a throttle valve controlling the supply of steam to the cylinders and a lever for operating said throttle valve, said lever having a latch mechanism; of a train line pipe supplied with air under pressure, a valved exhaust pipe leading therefrom and having an exhaust valve disposed in position to be tripped in passing an obstruction, a cylinder, a pair of pistons working in the cylinder and operatively connected to the lever and latch mechanism respectively, valves communicating with the cylinder, train line and exhaust pipe for initially releasing the latching mechanism and operating the lever to cut off the throttle valve and permitting the escape of air from the train pipe upon the opening of said exhaust valve to simultaneously apply the brakes, and means for returning said pistons to their initial positions, said latch mechanism having an operating handle connected thereto to permit disengagement of the latch moving the handle by one of the pistons whereby injury to the operator is prevented.

5. An automatic power cut-off and braking device for trains, comprising the combination with a locomotive having engine cylinders, a throttle valve controlling the supply of steam to the cylinders and a lever for operating said throttle valve, said lever having a latch mechanism; of a train line pipe supplied with air under pressure, a valved exhaust pipe leading therefrom and having an exhaust valve disposed in position to be tripped in passing an obstruction, a cylinder, a pair of pistons working in the cylinder and operatively connected to the lever and latching mechanism respectively, tandem valves having casings associated with the cylinder, said valves being under

train line pressure at one end and under exhaust pipe pressure at the other end, means establishing communication between one valve casing behind each of said pistons and adapted upon the exhaust of air by opening of the exhaust valve to permit movement of said valves whereby air under pressure will escape to successively operate said pistons for successively releasing the latch 5 and moving the throttle lever to close the throttle valve, means permitting the exhaust of air from said casing when the valves are in their initial positions, means to return said valves and pistons to their initial positions 10 and means establishing communication between the other valves and the train line pipe to permit the exhaust of air from the train line pipe for applying the brakes upon the shifting of said valves. 15

6. An automatic power cut-off and braking device for trains, comprising the combination with a locomotive having engine cylinders, a throttle valve controlling the supply of steam to the cylinders and a lever 20 for operating said throttle valve, said lever having a latch mechanism; of a train line pipe supplied with air under pressure, a valved exhaust pipe leading therefrom and having an exhaust valve disposed in position 25 to be tripped in passing an obstruction, a cylinder, a pair of pistons working in the cylinder and operatively connected to the lever and latch mechanism respectively, tandem valves having casings associated 30 with the cylinder, said valves being under train line pressure at one end and under exhaust pipe pressure at the other end, means establishing communication between one valve casing behind each of said pistons and adapted upon the exhaust of air by opening of the exhaust valve to permit movement of said valves whereby air under pressure will escape to successively operate said pistons for successively releasing the latch 35 and moving the throttle lever to close the throttle valve, means permitting the exhaust of air from said casing when the valves are in their initial positions, means to return said valves and pistons to their initial positions, means establishing communication between the train line pipe and the other valve casing between certain portions of the tandem valves thereof to normally prevent the escape of air from said train line pipe and an exhaust valve moved into communication with the train line pipe on the shifting of the last mentioned valve to permit the escape of air therefrom up to a predetermined pressure whereby the air in the train line pipe is conserved. 40 45 50 55 60

In testimony whereof I have signed my name to this specification in the presence of two subscribing witnesses.
